UNITED STATES PATENT OFFICE.

STEPHEN CASTLEMAN, OF BELZONA, MISSISSIPPI.

GRABOT-GIN SYSTEM.

SPECIFICATION forming part of Letters Patent No. 731,855, dated June 23, 1903.

Application filed July 28, 1902. Serial No. 117,296. (No model.)

To all whom it may concern:

Be it known that I, STEPHEN CASTLEMAN, a citizen of the United States, residing at Belzona, Washington county, State of Mississippi, have invented certain new and useful Improvements in Grabot-Gin Systems, of which the following is a specification.

My invention relates to certain new and useful improvements in grabot-gin systems, which systems are especially designed for treating lumpy cotton or grabots and the bolls as they come from the ordinary gins to save as much of the lint which would otherwise go to waste and to remove any remaining lint from the seed. My system is designed to automatically effect these purposes and to effectually separate and handle the seed and bolls after they have passed through the grabot, so as to minimize the loss of seed as much as possible.

The objects of my invention are, as above stated, to mechanically handle the seed, bolls, and grabots to the grabot-gins and to take the seed and bolls from these latter and separate and dispose of them with a single fan. I carry out these objects as will be more fully hereinafter set forth in the specification, drawings, and claims.

In the drawings, Figure 1 is a sectional elevation of the gin-house and one side of the boiler or fuel room, showing generally a side elevation of the devices used in my system. Fig. 2 is a detail section showing the end of the shaker, which will be hereinafter more fully referred to, and of the discharge-spouts. Fig. 3 is a plan view of the shaker, the discharge-spouts, and the feed-hopper. Fig. 4 is a plan view showing arrangement of the fan and piping to and from same.

Referring now to the drawings, in which like numerals indicate the same or like parts in all the views, 1 is a boll-screen from which the overflow-seed, with lint attached, the grabots, and the bolls drop into a hopper 2, from which they are conveyed by suction through the pipe 3 to the automatic discharge-valve or separator 4.

5 is a discharge-pocket, having a door 6, which will open, as shown by the dotted line 6^a, when struck by any heavy foreign sub-

stance, such as a pebble, which may have been carried up with the bolls and grabots.

In the separator 4 the bolls and grabots are separated from the conveying air and are dropped out into the grabot-room 7, in which room they may be stored, if, as is generally the case, it is so desired. From this room they are fed through a chute 8 into the grabot-gin 9, and there are effectually torn to pieces and all possible lint removed from the seed, which 60 lint passes out at the back end of the gin over a slow-speed condenser 10 and is collected by same into a vat suitable for baling. The seed and bolls drop through the spout 11 to a shaker 12. This shaker has a screen-bottom 65 13, extending, as will be seen by reference to Fig. 2, to the lower end of same and a solid bottom 14. Seed and bolls dropping on this shaker are separated, the seed dropping through the screen 13 and being carried by the 70 bottom 14 to the lower end of the table, where they drop into the spout 15. The bolls being too large to pass through the meshes of the screen pass over the lower end of same and drop into the spout 16. The seed and bolls 75 are carried by their respective spouts 15 and 16 to the feeder 17, which is divided (see Figs. 3 and 4) into two compartments 18 and 19, which respectively receive the seed and bolls and feed them into the conveyer-tubes 20 and 80 21, which lead to the seed-room and the fuel-heaps, respectively. These tubes are furnished with air by a fan 22, which is connected by a suction-tube 23 with the separator 4. 85 24 is a cylinder into which the bolls are blown tangentially at one side, so that they follow the inside of the cylinder until their speed is checked, so that they may drop straight to the ground. It will be seen that by my system I secure the suction and a double discharge-pipe from a single fan and that I separate and recover the seed from the grabot-gin as well as from the regular gin. I have not illustrated the details of the mechanism herein described, as the machines used are of 95 standard types and the system only is involved.

It will of course be evident that should it not be desired to re-treat the cotton and seed this system may be utilized in a direct wagon. 100

to-gin system with the single substitution of an ordinary gin for a grabot-gin.

Having fully described my invention, what I claim, and desire to secure by Letters Patent of the United States, is—

1. In a grabot-gin system, the combination with the gin, a suction-pipe, a feed-hopper thereon, an automatic trap for foreign substances and a separator discharging to said gin, of a shaking-table, parallel spouts beneath the discharge end of said table, a feeder divided into two compartments, one beneath each of said spouts, parallel conveyer-tubes below said compartments, and a single fan blowing air through said tubes, substantially as shown and described.
2. In a gin-elevator system, the combination

with the gin, a shaking-table to separate the seed and bolls, and discharge-tubes therefrom, of a fan, a suction-pipe for elevating the seed and bolls, leading to said fan and having a separator thereon, parallel conveyer-tubes leading from said fan and a feeder on said conveyer-tubes, having one compartment beneath each of said discharge-tubes, substantially as shown and described.

In testimony whereof I have signed my name to this specification in the presence of two subscribing witnesses.

STEPHEN CASTLEMAN.
